UNITED STATES PATENT OFFICE

2,080,626

TUBE

Oliver W. Mojonnier, River Forest, Ill.

Application June 18, 1936, Serial No. 85,975

1 Claim. (Cl. 138—38)

This invention relates to tubing and more particularly to tubing which may be used for heat exchange purposes or may be used for mixing of different liquids.

5 An object of this invention is to provide a tube or pipe which may be constructed from sheet metal and which is provided on the interior thereof with alternately spaced opposed projections which provide a tortuous passage for 10 liquid flowing through the tubing so that this liquid will be mixed thoroughly in its passage through the tube without in any way impeding the flow of the liquid through the tube.

Another object of this invention is to provide 15 a tube which may be constructed of relatively thin sheet metal and which includes means whereby the metal is strengthened so that it will not readily bend.

A further object of this invention is to provide 20 a tube which is constructed of opposed grooved members constructed of relatively thin sheet metal and provided with flanges on the opposing edges thereof, with the flanges of one grooved member confronting the flanges of the 25 other grooved member and securing the confronting flanges together as by soldering or welding so that these flanges will also assist in preventing the bending of the tube.

The above and various other objects and advantages of this invention will in part be described 30 in, and in part be understood from the following detail description of the present preferred embodiment, the same being illustrated in the accompanying drawing, wherein:—

35 Figure 1 is a fragmentary front elevation of a tube constructed according to an embodiment of this invention.

Figure 2 is a longitudinal section taken on the line 2—2 of Figure 1.

40 Figure 3 is a transverse section taken on the line 3—3 of Figure 1.

Referring to the drawing wherein like symbols designate corresponding parts throughout the several views, the numeral 10 designates generally one-half of a tube and the numeral 11 designates a confronting half section of a tube constructed according to an embodiment of this invention. These sections 10 and 11 are identical in construction and are formed from an 45 elongated relatively thin sheet of metal. The section 10 is constructed with a longitudinally grooved portion 12 and with marginal flanges 13 extending along the longitudinal edges of the grooved intermediate portion 12. The grooved portion 12 is provided with a plurality of detents 14 which provide convex projections substantially oval shaped on the inside of the grooved portion 12.

The other section 11 comprises an intermediate 50 grooved portion 15 and marginal flanges 16 which

are adapted to confront the marginal flanges 13 of the tube section 10. The confronting flanges 13 and 16 are secured together by suitable fastening means and, in the present instance, these flanges 13 and 16 are secured together as by 5 soldering or welding 17. When the two grooved portions 12 and 15 are secured together, they provide an oval or elliptical shaped tube but it will, of course, be understood that the particular configuration of the tube in transverse section 10 may be varied to suit the desires of the user. The tube section 11 is provided with a plurality of 10 detents 18 which are longitudinally spaced apart and are convex on the inside of the groove with the shape of the detents 18 similar to the shape 15 of the detents 14. The detents 18 are alternately spaced one between each pair of detents 14, so that the detents in the opposite sides of the tube will not impair the flow of any liquid through the tube but, at the same time, will provide a tortuous passage inside the tube so that several kinds of liquids may be discharged into the tube and by reason of the tortuous passage provided by the detents 14 and 18 these different 20 liquids will be thoroughly mixed as the liquids flow through the tube. These detents will also provide a means whereby the heat exchange, that is, either hot or cold, may be more readily effected and in this manner the tube herein disclosed may be used for either cooling or heating 25 of a liquid or liquids.

The detents 14 and 18 by reason of their convex construction and by reason of the oval shape thereof, will also eliminate the possibility of any accumulation of solids within the tube, as these 30 projections will provide a tortuous passage inside the tube which is so constructed that the flow of the material through the tube will carry along all of the liquids which will not, at any time, be pocketed by reason of the projections forming 35 the tortuous passage.

It is, of course, understood that various changes and modifications may be made in the details of construction and design of the above 40 specifically described embodiment of this invention without departing from the spirit thereof, such changes and modifications being restricted only by the scope of the following claim.

I claim:—

A tube comprising an elongated tubular body 50 constructed of opposed grooved members providing an elliptical tube in transverse section, longitudinal flanges carried by the longitudinal edges of the members, means for securing the confronting flanges together, and spaced apart 55 convex projections carried by each member, the projections of one member being alternately spaced with respect to the projections of the other member.
